UNITED STATES PATENT OFFICE.

THOMAS NORTHEY, OF TORONTO, ONTARIO, CANADA.

STEAM-ACTUATED VALVE.

SPECIFICATION forming part of Letters Patent No. 287,706, dated October 30, 1883.

Application filed August 15, 1883. (No model.)

To all whom it may concern:

Be it known that I, THOMAS NORTHEY, a subject of the Queen of Great Britain, and a resident of Toronto, in the Province of Ontario and Dominion of Canada, have invented certain new and useful Improvements in Steam-Actuated Valves; and I do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal vertical section 15 of a steam-cylinder and steam-chest, showing the valve in position in the middle of the steam-chest or on the half-stroke. Fig. 2 is a vertical cross-section through the middle of the cylinder, valve, and steam-chest. Fig. 3 20 is a horizontal sectional view through line xx , Fig. 1, looking downward. Fig. 4 is a plan view of the bottom of the steam-chest which constitutes the valve-seat, and Fig. 5 is a plan view of the under side of the slide-valve.

Similar letters of reference indicate corresponding parts in all the figures.

My invention has relation to steam-actuated valves, adapted more particularly to steam-engines as applied to steam-pumps; and the 30 object of my invention is to so construct the valve that it may be operated with absolute certainty, and with a minimum of wear and friction by the steam it admits into the cylinder, and without the intervention of any mechanical contrivance. In other words, my 35 improved steam-actuated slide-valve is a "balanced" valve, which is operated by the direct action of the steam on the valve, and without the intervention of a plunger or other 40 intermediate mechanism.

In the accompanying drawings, A represents the steam-cylinder, and B the piston.

D and D' are the usual steam-ports, which extend from each end of the cylinder to the 45 steam-chest C.

F and F' are auxiliary steam-ports, communicating between the interior of the cylinder and the interior of the steam-chest on opposite sides of the main ports D and D'. By 50 arranging the auxiliary ports on opposite sides

of the main ports, it will be seen that the former do not come in contact with or otherwise interfere with the latter.

E² is the ordinary exhaust-port, which is formed in the bottom of the steam-chest, and 55 communicates, in the usual manner, with the exhaust-port E' in the valve.

My improved steam-actuated balanced slide-valve has three compartments—viz., a central chamber, E, and the end chambers, M and M', 60 one at each end; and the live steam is fed into the central chamber from the throttle-valve, below the center of the slide-valve, through the steam-ports J. A small steam-channel, R, is cut through the top of the central chamber or compartment, E, opening up into a steam-chamber, S, located in the top part of the steam-chest, so that the steam fed into chamber S will exercise a downward pressure upon the body of the valve, irrespective of 65 its position in the steam-chest, which will equalize or balance the upward pressure on the valve caused by the steam admitted to its inside and from the cylinder. The valve is provided on its under side with the steam-ports G and G', through which steam may be 70 fed from the cylinder, by way of the auxiliary steam-ports F and F', into opposite ends of the steam-chest, for the purpose of reciprocating the valve. The valve is further provided with exhaust-ports P and P', which are 75 so located as to operate in conjunction with their corresponding ports, Q and Q', in the steam-chest, which said ports Q and Q' communicate with the general exhaust. 80

As represented in Fig. 1 of the drawings, the piston is shown at the end of its right-hand stroke, and the valve is in the midway position in the steam-chest, with all the ports closed except the exhaust. As the piston 90 starts on the return-stroke, actuated by the initial steam-pressure, the valve will be in position to cut off communication with the auxiliary steam-port F' and with the cylinder, and the cylinder will exhaust through 95 ports D and F. When the piston has passed the auxiliary port F on its stroke from right to left, the valve will have reached the end of its left-hand stroke, and the steam admitted into the steam-chest through the auxiliary 100

port F will pass through port G in the valve and the corresponding port, H, in the bottom of the steam-chest into the left-hand end of the latter, where it operates to shift the valve 5 to the other end of the steam-chest, ready to effect the return-stroke of the piston. As the valve slides from left to right in the steam-chest, the ports P and Q will gradually cover and open communication with each other at 10 the end of the stroke, but not before, thus exhausting the steam by which the valve was actuated on the right-hand stroke through the port N, chamber M, port P, port Q, and the general exhaust, with which the latter port 15 communicates. The valve will exhaust in like manner, at the end of its return-stroke from right to left, through the port N', chamber M', valve-port P', and the port Q' in the steam-chest, which communicates with the 20 general exhaust the same as the corresponding port, Q, in the other end of the chest.

In order to give the valve proper momentum to initiate its strokes, it may be loaded by introducing fine shot into the end chambers, M 25 and M', and after the proper gravity has been attained the shot is melted down upon the bottom of the valve, so as to remain permanently in position; and in order to prevent undue jarring of the valve as it reciprocates 30 in the steam-chest, the latter may be provided at opposite ends with suitable cushions, *a* and *a'*.

Having thus described my invention, I do not claim, broadly, a steam-actuated valve 35 operated by the direct action of the steam it admits into the steam-cylinder; but

What I claim as my improvement, and desire to secure by Letters Patent of the United States, is—

1. The triple-chambered slide-valve composed of the central compartment, E, having exhaust-port E', live-steam port J, and steam-channel R, and the end compartments, M and M', provided, respectively, with the ports G N P and G' N' P', constructed and arranged 45 substantially as and for the purpose shown and set forth.

2. The triple-chambered slide-valve E M M', having end apertures, N and N', whereby the chambers M and M', located at opposite 50 ends of the valve, may be loaded with a weight to properly regulate its momentum, substantially as set forth.

3. The combination of the steam-cylinder A, having exhaust E', main ports D D', and auxiliary ports F F', a valve-seat having ports cut through it corresponding to and communicating with the cylinder-ports, the steam-chest having the steam-chamber S, live-steam ports H H', and ports Q Q', communicating 60 with the general exhaust, and the triple-chambered slide-valve having central compartment, E, provided with the live-steam port J, exhaust E', and steam-channel R, and end compartments, M and M', provided, respectively, with 65 the ports G N P and G' N' P', the whole constructed and combined to operate substantially in the manner and for the purpose herein shown and set forth.

In testimony that I claim the foregoing as my own I have hereunto affixed my signature in presence of two witnesses.

THOMAS NORTHEY.

Witnesses:

LOUIS BAGGER,
AUGUST PETERSON.
